[57] CLAIM

The ornamental design for a bottle, as shown and described.

DESCRIPTION

FIG. 1 is a perspective view of a bottle showing my new design with a spout attachment shown in broken lines for illustrative purposes only;

FIG. 2 is a left side elevational view thereof;

FIG. 3 is a front elevational view of the embodiments of FIGS. 1, 6, 8 and 10;

FIG. 4 is a right side elevational view of the embodiments of FIGS. 1, 6, 8 and 10;

FIG. 5 is a bottom plan view of the embodiments of FIGS. 1, 6, 8 and 10;

FIG. 6 is a perspective view of a second embodiment of a bottle showing my new design with the compressed spout attachment shown in broken lines for illustrative purposes only;

FIG. 7 is a left side elevational view of the second embodiment;

FIG. 8 is a perspective view of a third embodiment of a bottle showing my new design with a spout attachment shown in broken lines for illustrative purposes only;

FIG. 9 is a left side elevational view of the third embodiment;

FIG. 10 is a perspective view of a fourth embodiment of a bottle showing my new design with a spout attachment shown in broken lines for illustrative purposes only; and,

FIG. 11 is a left side elevational view of the fourth embodiment.
